J. MARKIN

COMBINATION RAINCOAT AND JACKET

Filed Jan. 31, 1927

Patented Jan. 3, 1928.

1,654,691

UNITED STATES PATENT OFFICE.

JOSEPH MARKIN, OF CHICAGO, ILLINOIS.

COMBINATION RAINCOAT AND JACKET.

Application filed January 31, 1927. Serial No. 164,737.

My invention relates to a combination raincoat and jacket, and it has for its object the provision of a new and improved form and arrangement of parts by the use of which the garment may be worn as a full-length raincoat or alternatively as a jacket. It is one of the objects of my invention to provide improved means for holding up the lower portion of the coat folded in such condition as to be unobjectionable for wear. It is another object of my invention to provide a combination coat and jacket of this type which can be very easily and quickly manipulated for the transformation from the jacket form to the full-length coat form, such transformation being preferably accomplished by the wearer without taking off the garment, the arrangement being such that the transformation to the jacket form can be accomplished without difficulty.

It is another object of my invention to improve garments of this type in sundry details hereinafter pointed out. The preferred means by which I have accomplished my objects are illustrated in the accompanying drawing and are hereinafter specifically described. That which I believe to be new and desire to cover by Letters Patent is set forth in the claims.

30 In the drawing,

Fig. 1 is a front view, partly broken away, of my improved full-length coat.

Fig. 2 is a front view, also partly broken away, showing the condition of the coat as 35 folded up in jacket form.

Fig. 3 is a fragmentary inside face view of the lower portion of the coat at one side thereof, with the corner turned up preparatory to folding the garment into its jacket 40 form.

Fig. 4 is a fragmentary inside face view of the corresponding lower portion of the coat at the opposite side thereof as compared with Fig. 3 but with the garment 45 folded into its jacket form; and

Fig. 5 is a vertical sectional view taken at line 5—5 of Fig. 4.

Referring to the several figures of the drawing, in which corresponding parts are 50 indicated by the same reference characters, 10 indicates the skirt portion of my improved coat, 11 and 12 the sleeves, 13 the collar, and 14 the front panel or facing which is secured at both edges along its upper end portion but which is loose at the 55 rear edge at its lower end portion so as to

receive a fold between it and the body of the coat as hereinafter described. The form of the coat as indicated in Fig. 1 is very similar to that of the ordinary raincoat of 60 the straight form type.

As is shown in Fig. 3, when the coat is to be transformed into its jacket form, the lower corner 15 at each side of the coat is

folded up along a diagonal line on the outer 65 face of the skirt 10, being secured in such turned position by means of a snap 16, preferably of the glove fastener type, one member of the snap being mounted upon the corner of the flap and the other member being mounted upon the outer face of the skirt of the coat.

In Fig. 4, the corner flap 15 at the opposite side of the coat is indicated as being folded in like manner and held in position by the flap 16 at that side. After the corner flaps 15 have been secured in their folded-up position, the skirt 70 of the coat is folded up on the inner face of the coat, the fold being made along the line indicated in Fig. 3 at 17, the bottom edge of the skirt being secured in such folded-up condition by means of releasable devices 18 also preferably of the glove fastener type. The arrangement is such that the skirt 10 when so folded up and secured 75 by the snap devices 18 lies smoothly against the inner face of the upper portion of the coat.

After the skirt 10 has been folded up in position as described, the lower edge portion of such fold is again folded, this time 80 along the line indicated in Fig. 3 at 19, such

second fold in the skirt portion coming at the line 20 which is then in position directly opposite the line 19. The second fold is 85 made upwardly and outwardly rather than inwardly, such fold being secured in folded-up position by the use of releasable securing devices 21, also preferably in the form of glove fasteners.

The second fold, which is indicated by the numeral 22 extends at its 90 end portion underneath the facing panel 14, as is clearly shown in Fig. 2. With the garment folded up in jacket form, a tongue 95 or flap 23 is utilized for securing the bottom of such jacket at one side to the bottom at 100 the opposite side, such flap 23 being provided with a releasable fastener 24 of the glove fastener type, as is clearly shown in Fig. 2. When the garment is being worn in the full-length coat form, the flap or 105 tongue 23 is held folded back releasably in position by the use of a glove fastener mem-

ber 25 which is adapted to cooperate with the member 24 carried by the flap, as is shown in Fig. 1.

When the garment is being worn in jacket form as shown in Fig. 2 and when the wearer desires to transform the garment into the full-length coat form, he is able to do so without taking off the garment. He finds it a very easy matter to release the devices 21 for turning the fold 22 down on the outside, then to release the snaps 18 for turning the skirt 10 down from its position on the inside, and then to release the snaps 16 for turning down the corner flaps 15. If he desires, he can readjust the collar and lapel portion of the garment into the position as shown in Fig. 1 by the ordinary manipulation for this purpose.

When it is desired to transform the garment from the full-length coat to the jacket form, this can be accomplished to the best advantage by taking the garment off, but it will be appreciated that it could be done in case of necessity without taking the garment off.

I have found in actual use of my improved garment that the garment is very neat and very satisfactory in every way in either of its two forms, and that the transformation from the one form to the other can be accomplished quickly and readily without any great inconvenience. The snap devices which are seen on the outer face of the coat are preferably made to conform in color with the parts upon which they are seen. At the points where a member of a snap device is located upon the body of the coat away from the hem or other double portion, the body of the coat is preferably reinforced, as indicated, for example, at 26 at various points in the drawing. I have found that the construction is very strong so as to be suitable for hard usage. I have also found that the garment is very attractive and neat in either of its two forms.

While I prefer to employ the form of con-

struction as illustrated in my drawing and as above described, I wish to have it understood that I do not limit my invention to the form as shown except so far as certain 50 of the claims are specifically so limited, since it will be appreciated that changes might well be made in the garment without departing from the spirit of my invention.

I claim:—

1. A combined raincoat and jacket, comprising in combination a long coat, releasable means for holding the lower corners thereof folded up along diagonal lines, and other releasable means for holding the lower portion of the coat folded up smoothly to form 60 a jacket.

2. A combined raincoat and jacket, comprising in combination a long coat, releasable means for holding the lower portion 65 thereof folded up smoothly inside, and other releasable means for holding the lower portion of such folded part folded up smoothly outside.

3. A combined raincoat and jacket, comprising in combination a long coat, releasable means for holding the lower portion thereof folded up smoothly inside, other releasable means for holding the lower portion 75 of such folded part folded up smoothly outside, and a tongue projecting from the front edge at one side adjacent to the second fold for securing the two side portions together when the garment is worn as a jacket.

4. A combined raincoat and jacket, comprising in combination a long coat, releasable means for holding the lower portion thereof folded up smoothly inside, other releasable means for holding the lower portion 85 of such folded part folded up smoothly outside, and a flap at the front edge at one side under which the second folded portion extends when the garment is worn as a jacket.

JOSEPH MARKIN.
